Primary Examiner — Jeffrey D Asch(57) **CLAIM**

The ornamental design for a walkie talkie, as shown and described.

DESCRIPTION

FIG. 1 is a front elevational view of a walkie talkie showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof; and,

FIG. 8 is another perspective view thereof.

The broken lines shown in the drawing are included to illustrate portions of the article that form no part of the claimed design. The interior surfaces of the rear screw openings, recessed beyond thin edge thickness, and shown without shading in FIGS. 3-6 and 8, form no part of the claimed design.
